BILLFOLD OR SIMILAR ARTICLE

Samuel J. Smallman, New York, N. Y.

Application May 28, 1953, Serial No. 25,221

Term of patent 14 years

(CL. D87—3)

To all whom it may concern:

Be it known that I, Samuel J. Smallman, a citizen of the United States of America, residing in New York city, county of New York, and State of New York, have invented a new, original, and ornamental Design for a Billfold or Similar Article, of which the following is a specification, reference being had to the accompanying drawing, forming part thereof.

Fig. 1 is a front perspective view of a billfold or similar article showing my new design.

Fig. 2 is a plan view in open position.

Fig. 3 is a fragmentary plan view of the billfold with the purse portion removed from the billfold.

The rear of the billfold is substantially plain.

I claim:

The ornamental design for a billfold or similar article, substantially as shown and described.
